[57] **CLAIM**

The ornamental design for a disc media storage rack, as shown and described.

DESCRIPTION

FIG. 1 is a front right perspective view of the design of a disc media storage rack of this invention;

FIG. 2 is a plan view of the front face of the disc media storage;

FIG. 3 is a rear plan view of the disc media storage rack of this invention;

FIG. 4 is top plan view of the disc media storage rack of this invention;

FIG. 5 is a bottom plan view of the disc media storage rack of this invention;

FIG. 6 is a left hand plan view of the disc media storage rack of this invention; and,

FIG. 7 is a right hand plan view of the disc media storage rack of this invention.

The broken line showings throughout the drawings are for illustrative purposes only and form no part of the claimed design.
